J. S. Patric

UNITED STATES PATENT OFFICE.

JOHN S. PATRIC, OF VICTOR, NEW YORK.

IMPROVED AIR-COMPRESSING APPARATUS.

Specification forming part of Letters Patent No. 47,328, dated April 18, 1865.

To all whom it may concern:

Be it known that I, JOHN S. PATRIC, of Victor, in the county of Ontario and State of New York, have invented a new and useful apparatus for compressing air by means of water to drive air-engines and for other mechanical purposes; and I do hereby declare that the following is a full, clear, and exact description thereof, reference being had to the accompanying drawings, making a part of this specification, in which—

Figure 1 is a vertical longitudinal section of my invention, taken in the direction of the red line *x* in Fig. 2, a portion of the lower end of the water-pipe *P'* being removed to show the valve *a*. Fig. 2 is a transverse section of the same in the plane of the red line *o* in Fig. 1.

Similar letters of reference indicate corresponding parts in both figures.

The object of this invention is to compress air by means of a column of water, which air may be readily conveyed in pipes to convenient localities to supply atmospheric engines for driving machinery, &c.; and it consists in the employment or use for that purpose of a reservoir or chamber composed of two compartments, which are separated by a flexible diaphragm connected to an adjusting-bar that operates the inlet and outlet water-valves of each chamber.

The details of the construction will be better understood by reference to the drawings and specification.

To enable others to make and use my invention, I will describe its construction and operation.

A and *A'* in the drawings represent the two compartments in which the air is compressed by the pressure of the water forced in through the pipes *P* and *P'* under a "head". *B* is the web to which the flexible diaphragm *d* is secured by the metallic ring *h*, which is held by rivets or otherwise. *C* and *C'* are guides or supports for the ends of the adjusting bar or screw *s*; *D D*, the domes into which the floats *F* and *F'* rise alternately; *E* and *E'*, the outlet water-valves; *G* and *G'*, the valves through which the compressed air escapes from the compressing-chambers; *H* and *H'*, the inlet air-valves.

The reversing bar or screw *s* is attached to

the diaphragm *d* by clamping the disks *y* between the nuts *m*. The arms *J* of the inlet-valves are secured to the bar *s* by the set-nuts *n*, and the top of the arms *I* of the outlet-valves *E* and *E'* is connected loosely to the arms *J*. The ends of the bar *s* are allowed to slide freely in the guides *C*. Each pair of the jointed levers *f* and *f'* are hinged at one end to the ears projecting from the bent rods *b*, which are rigidly fixed to the web *B*. The other ends are hinged to the studs *c* and *c'*, which may be tapped onto the bar or screw *s*, as seen in Fig. 1, or they may be fitted loosely and supported between jam-nuts, similar to the arms *J*, which might be more desirable for varying the longitudinal throw of the screw. The pivot of the center joint of these levers receives the float-rods *r*. There is a stop, *e*, attached to one of the jointed levers in each compartment, and as the water is discharged from either its float drops until the stop *e* rests upon the screw *s*. The middle joint of the levers should drop a trifle below the center of the end joints, as shown in the left hand chamber in Fig. 1, which effectually locks the screw *s* and the diaphragm *d* in their present position until they shall be released by the next influx of water in that compartment, which raises the float, and the pressure of the water against the flexible diaphragm forces it and the screw *s* to their opposite position, and the stud *c'* being also moved back allows the levers *f'* and the float *F'* to drop to the position shown by those in the opposite chamber.

This apparatus is placed at the foot of the fall or column of water which is supplied to the compartments *A* and *A'* alternately through the pipes *P* and *P'*. The relative position of the parts in the two chambers is shown in Fig. 1, as just previous to a change which will empty chamber *A* and fill *A'*.

When the water in *A* rises a little above the height indicated by the red dotted line in chamber *A*, the float *F* and levers *f* are raised, the same as indicated by those in the opposite chamber, and the bar *s* being thereby released the pressure of the water against the diaphragm, as before stated, forces it to its opposite position, which opens valves *E* and *a* and closes *E'*, and that in the lower end of pipe *P*, all of which are locked in that position by the

fall of the float and levers in chamber A', and the valves G and H' are at once closed and H and G' opened.

The air is supplied through the valves H and H', and the compressed air is sent off for use through valves G and G', which may communicate with one common reservoir.

The valves H and H' may be attached to the top instead of at the sides by applying a light spring to keep them closed when necessary.

The floats F and F' may be flattened, if desired, to make them more sensitive upon the water.

The pendants g guide the floats F and F' into the domes, and there should be three or more for each float.

A single chamber may be used by attaching the two water-valves to a weighted lever hinged at the bottom, and the top being thrown each way past the center by the rising and falling of the float alternately. This would

be less desirable perhaps than the double chamber, because its action would be intermittent.

What I claim as my invention, and desire to secure by Letters Patent, is—

1. The combination of the floats F and F', with the diaphragm d, with the inlet and outlet water-valves a and E and E', all the parts being arranged and operating within the air and water chamber.

2. Operating the water-valves a and E by the bar s, which is connected to the flexible diaphragm d, substantially as set forth.

3. The combination of the floats F and F' with the jointed levers f and f', arranged and operating substantially in the manner and for the purpose shown and described.

J. S. PATRIC.
